(57) **CLAIM**

The ornamental design for a draw bar, as shown and described.

DESCRIPTION

FIG. 1 is a rear-left perspective view of a draw bar;

FIG. 2 is a front-right perspective view thereof;

FIG. 3 is a rear view thereof;

FIG. 4 is a front view thereof;

FIG. 5 is a left-side view thereof;

FIG. 6 is a right-side view thereof;

FIG. 7 is a top view thereof, and,

FIG. 8 is a bottom view thereof.

The broken lines shown in the drawings depict portions of the article and form no part of the claimed design.

1 Claim, 8 Drawing Sheets
